(57) **CLAIM**

We claim the ornamental design for a lighting fixture, as shown and described.

DESCRIPTION

FIG. 1 is a bottom perspective view of the claimed design;

FIG. 2 is a top perspective view of the claimed design;

FIG. 3 is a side view of the claimed design;

FIG. 4 is a top view of the claimed design;

FIG. 5 is a bottom view of the claimed design;

FIG. 6 is a front view of the claimed design; and,

FIG. 7 is a rear view of the claimed design.

The ornamental design which is claimed is shown in solid lines in the figures.

The broken lines illustrate portions of the lighting fixture which form no part of the claimed design.
